UNITED STATES PATENT OFFICE.

PETER A. CURTIN, OF BUFFALO, NEW YORK.

DESIGN FOR A MILK-BOTTLE CAP OR STOPPER.

54,606.

Specification for Design.

Patented Mar. 9, 1920.

Application filed June 29, 1917. Serial No. 177,811. Term of patent 7 years.

To all whom it may concern:

Be it known that I, PETER A. CURTIN, a citizen of the United States, residing at Buffalo, in the county of Erie and State of New York, have invented a certain new, original, and ornamental Design for a Milk-Bottle Cap or Stopper, of which the following is a specification, reference being had to the accompanying drawings, forming part thereof, in which—

Figure 1 is a side elevation of the cap or stopper illustrating my new design.

Fig. 2 a diametral section of the same.

Fig. 3 is a top plan view of the same.

Fig. 4 an inverted view of the same.

I claim:

The ornamental design for a milk bottle cap or stopper, as shown.

PETER A. CURTIN.

Witness:

EMIL NEUHART.
